United States Patent Office

Des. 177,970
Patented June 12, 1956

177,970

BUTTER DISH

Harold L. Fulton, Elyria, Ohio

Application July 18, 1955, Serial No. 37,000

Term of patent 3½ years

(Cl. D44—5)

Fig. 1

Fig. 3

Fig. 2

Fig. 4

Figure 1 is a top plan view of a butter dish, showing my new design;

Figure 2 is a side elevational view thereof;

Figure 3 is a cross-sectional view thereof, taken on the line 3—3 of Fig. 1; and

Figure 4 is an end view thereof.

I claim:

The ornamental design for a butter dish, substantially as shown.

References Cited in the file of this patent

UNITED STATES PATENTS

D. 157,729 Bliss _____ Mar. 21, 1950
D. 173,027 Gershen _____ Sept. 14, 1954